UNITED STATES PATENT OFFICE.

ROBERT N. COX, OF WAUKEGAN, ILLINOIS.

MAGAZINE-PISTOL.

1,369,401.

Specification of Letters Patent. Patented Feb. 22, 1921.

Application filed June 24, 1920. Serial No. 391,490.

To all whom it may concern:

Be it known that I, ROBERT N. Cox, a citizen of the United States, residing at Waukegan, in the county of Lake and State of Illinois, have invented certain new and useful Improvements in Magazine-Pistols; and I do hereby declare the following to be a full, clear, and exact description of the invention, such as will enable others skilled in the art to which it appertains to make and use the same.

This invention relates to magazine pistols and it consists in the novel features herein-after described and claimed.

An object of the invention is to provide a pistol of the character stated which is of simple and durable structure and which includes a cylinder slidably mounted in a barrel and spring means for moving the cylinder with relation to the barrel whereby the cylinder is held at a projected position with relation to the barrel when the pistol is fired.

A further object of the invention is to provide a magazine chamber in the cylinder adapted to retain the balls and a spring actuated follower located in the chamber and adapted to move the balls successively into the bore of the cylinder.

A further object of the invention is to provide a plunger member of improved structure having a disk which is interposed between the first mentioned spring and the end of the cylinder. The plunger member is provided with a stem portion which is adapted to move along the bore of the cylinder and project the ball therefrom. A locking mechanism is provided and is engageable with the disk to temporarily hold the same at a retracted position against the tension of the first mentioned spring and the said locking mechanism may be actuated to release the disk when the pistol is fired.

With these and other objects in view as will become more apparent as the description proceeds, the invention consists in certain novel features of construction, combination, and arrangement of parts as will be hereinafter more fully described and claimed.

For a complete understanding of my invention, reference is to be had to the following description and accompanying drawings, in which:

Figure 1 is a longitudinal sectional view,

illustrating a pistol constructed in accordance with my invention and showing the cylinder in retracted position.

Fig. 2 is a similar view illustrating the cylinder projected with relation to the 60 barrel,

Fig. 3 is a transverse sectional view, taken on the line 3—3 of Fig. 1,

Fig. 4 is a longitudinal section view, illustrating the cylinder, 65

Fig. 5 is a side elevation, illustrating the plunger,

Fig. 6 is an end view illustrating the same,

Fig. 7 is a similar view looking in the other end of the plunger, 70

Fig. 8 is a bottom plan view illustrating the cylinder.

The pistol comprises a barrel 1 which is preferably formed of sheet metal and is substantially cylindrical in shape. The barrel 75 1 is mounted on a stock 2 in a usual manner and the stock is provided with a trigger guard 3.

The barrel 1 is provided at its lower side with spaced flanges 4 and a stop block 5 is secured between the flanges 4 at the forward ends thereof. A lock member 6 is pivotally mounted between the flanges 4 at the rear ends thereof and a spring 7 is attached to the barrel and bears against the rear end of 80 the lock member 6 and serves to normally hold the forward end of the lock member in an elevated position between the flanges 4. A trigger 6^a is pivoted at 6^b and is provided with an arm 6^c which engages the lock member 6 as shown in the drawings. 85

A cylinder 8 is slidably mounted in the barrel 1 and is provided at its rear end with an L-shaped lug 9 that lies in the space between the flanges 4 and which is adapted to 90 engage under a shoulder 10 provided at the forward end of the stock 5 when the cylinder is projected with relation to the barrel.

The cylinder 8 is provided with a central longitudinal bore 11 that extends from end 100 to end thereof and the cylinder 8 is provided below the bore 11 with a longitudinally disposed magazine chamber 12. An orifice 13 connects the bore 11 with the chamber 12 at the inner portion thereof and a shunt block 105 14 is located in the rear end of the chamber 12 at a point behind the orifice 13. A follower 15 is slidably mounted in the chamber 12 and a spring 16 is interposed between the forward end of the follower and the forward 110

end of the chamber and is under tension with a tendency to normally hold the follower 15 toward the rear end of the chamber 12. The rear portion of the chamber 12 is 5 adapted to retain balls 17 arranged in a row or column and the rear end of the follower 15 bears against the end ball of the row.

The bottom wall of the chamber 12 has an elongated slot 12' with a circular opening 10 13' through which the balls may be placed in the chamber 12. The follower 15 normally overlies the circular opening 13' to close the same and has a lug 14' formed on one end that travels in the slot 12' and provides a construction whereby said follower 15 may be retracted to open the circular opening 13'. A pointed instrument may be used to retract the follower by placing the same against the lug 14'.

20 The pistol further includes the plunger 18 which is slidably mounted in the barrel 1 and which carries at a point between its ends a disk 19 that fits snugly in the barrel at a point behind the cylinder. A relatively 25 heavy coil spring 20 is interposed between the rear end of the barrel 1 and the rear face of the disk 19 and is under tension with a tendency to hold the disk away from the rear end of the barrel. The disk 19 is provided 30 at its lower side with a lug 21 which is received in the space between the flanges 4 of the barrel. When the plunger 18 is in a retracted position in the barrel, the forward end of the catch 6 engages against the forward surface of the lug 21 and holds the plunger member in a retracted position in the barrel against the tension of the spring 20. A rubber packing washer 22 is interposed 35 between the forward surface of the disk 19 and the rear or inner end of the cylinder 8. The cylinder 8 is provided above the bore 11 with a longitudinally disposed chamber 23 which receives a rod 24 formed on the plunger member 18. A 40 spring 25 is interposed between the forward end of the rod 24 and the forward end of the cylinder 8 and is under tension with a tendency to hold the cylinder at a projected position in relation to the rod 24. The 45 plunger member is further provided with a centrally positioned rod 26 which enters the inner part of the bore 11. The rod 26 is shorter in length than the rod 24.

The pistol may be operated as follows:

50 Assuming that the magazine chamber 12 is loaded with balls 17 and it is desired to bring one of the balls in the path of the movement of the rod 26, the cylinder 8 is moved to a retracted position in the barrel 1 to engage the lug 21 with the lock member 6. At this time, the spring 25 is compressed, and when the cylinder 8 is released, this spring moves it forwardly with respect to 55 barrel 1 and the rods 24 and 26 until the lug 9 engages the shoulder 10. This move-

ment of the cylinder 8 carries the orifice 13 beyond the forward end of the rod 26 and the spring 12 causes a ball 17 to be moved from the magazine chamber 12 into the bore 11 in front of the forward end of the rod 26. Now that the ball is in position in the bore 11, the lock member 6 is actuated whereby its end releases or disengages from the lug 21 of the disk 19 and the plunger member is forced in a forward direction by the spring 20, whereby the rod 26 strikes the ball and impels it in a forward direction beyond the end of the muzzle or outlet of the bore 11. The spring 25 is weaker than the spring 20 and consequently after the pistol has been fired the spring 25 will be compressed by the rod 24, whereby when the cylinder 8 is again moved rearwardly to engage the lug 21 with the lock member 6, the cylinder will, when released, be forced in a forward direction by the spring 25 and the orifice 13 will be again moved to a position where it is uncovered from the rod 26, therefore, another ball 17 may enter the bore 11 and this second ball may be projected from the pistol in a manner as hereinbefore described.

Having described the invention what is claimed is:

1. A pistol comprising a barrel, a cylinder slidably mounted therein and having a bore, and provided at the sides of the bore with chambers, one of the chambers being connected with the bore by means of an orifice, a spring pressed follower located in the chamber which is connected with the bore by the orifice, a plunger member slidably mounted in the barrel, a lock mounted upon the barrel and engageable with the plunger member to hold the same in a retracted position, a spring interposed between the plunger member and the barrel and tending to force the plunger member in a forward direction, the plunger member having a rod portion which enters one of the chambers in the cylinder, a spring interposed between the forward end of said rod portion and the forward end of the cylinder, said plunger member also having a rod member which enters the bore of the cylinder.

2. A pistol comprising a barrel, a cylinder slidably mounted therein, means for restraining the cylinder against turning movement with relation to the barrel, a spring actuated lock member pivoted upon the barrel, a plunger member slidably mounted in the barrel and having a portion which enters the cylinder, said lock member adapted to engage the plunger member to hold the same in a retracted position, a spring interposed between the plunger member and the cylinder, and a spring interposed between the plunger member and the barrel, the last said spring being of greater tension than the first mentioned spring.

3. A pistol comprising a barrel, a cylinder slidably mounted therein and provided with a bore and having chambers located at the sides of the bore, a spring pressed fol-
5 lower located in one of the chambers, the last mentioned chamber being provided with an orifice which communicates with the bore, the cylinder having an L-shaped lug which lies between the side portions of the
10 barrel, a stop member mounted upon the barrel and having a shoulder under which said lug may engage, a plunger member slidably mounted in the barrel and having a portion which enters the bore of one of
15 the cylinders, said plunger member having a rod portion which enters the other chamber of the cylinder, a spring interposed between the end of the cylinder and the last men-

tioned rod portion, the plunger member having a disk provided with a depending 20 lug, a cushion interposed between the disk and the cylinder, a spring interposed between the disk and the rear end of the barrel, the last mentioned spring being of greater tension than the first mentioned 25 spring, and a spring actuated catch device mounted upon the barrel and adapted to engage the lug of the disk to hold the plunger member in a retracted position against the tension of the heavier spring. 30

In testimony whereof I affix my signature in presence of two witnesses.

ROBERT N. COX.
